APPARATUS FOR MOLDING TUBULAR CONCRETE BODIES

Simon Lake, Milford, Conn.; Thomas A. E. Lake
administrator of said Simon Lake, deceased

Application January 26, 1944, Serial No. 519,804

7 Claims. (Cl. 25—30)

This invention relates to the molding of concrete, and it has special reference to the molding of tubular objects such as concrete pipes, particularly those which, in service, may be subjected to high internal pressures, and to the action of fluids and liquids, such as gases and petroleum products which normally cannot effectively be confined within walls of concrete due to the permeable nature of such walls.

One object of the invention is to provide for the rapid and uniform molding of tubular concrete bodies (pipe sections) in such a manner as to subject the concrete mix, during molding, to pressure adequate to thoroughly compact it, at the same time exhausting from it all air and excess moisture, thus ensuring a uniform texture free of the blow holes and voids which ordinarily result in the permeability of concrete bodies molded in accordance with the usual methods.

Another object is to provide for impregnation and/or coating of the molded bodies with pore-sealing or other compounds or agents tending to increase the impermeability of their walls and/or adapting them for use in the handling of substances to which concrete is normally permeable, such as corrosive liquids and gases.

In the accompanying drawings illustrating the invention, in the several figures of which like parts are similarly designated,

Fig. 1 is an axial, sectional elevation, taken on the line 1—1 of Fig. 2, showing one form of apparatus in accordance with the invention.

Fig. 2 is a partial sectional elevation taken on the line 2—2 of Fig. 1.

Fig. 3 is a view similar to Fig. 1, but showing a modified embodiment of apparatus in accordance with the invention, and

Fig. 4 is a partial sectional elevation taken on the line 4—4 of Fig. 3.

As shown in Figs. 1 and 2, the castings are preferably made in a vertical flask A, formed in halves and bolted together, with a strip of packing, not shown, between their flanged joints. The flask is bolted to a platen B, set into a concrete floor slab C, which has a well D, formed below it to receive the reciprocating hollow core E, which, in operation of the apparatus, forms the inner wall surface of the pipe. This reciprocating core is made of a tube, closed at its lower end as shown at 1, and a hydraulic cylinder F is secured at 2 in the reciprocating core, this cylinder having a fixed piston G shown near the top of the cylinder. A piston rod 3 extends from the piston down through a stuffing box 4

5 at the lower end of the cylinder and out through another stuffing box 5 at the lower head 1 of the reciprocating core, where it is secured in a flanged casting 6, secured to the floor 1 of the well. The piston rod 3 is provided with two passageways 8 admits to or discharges from the space 9 above the piston G water or other pressure fluid through pipe 10, and the other passageway 11 terminates 10 at a port 12 below the piston and is connected with a pipe 13 which permits water or other pressure fluid to be admitted to or expelled from the space 14 under the piston. The pipes 10 and 13 are shown as provided with two-way 15 valves 15 and 16, respectively, whereby pressure fluid flow to and from the spaces 9 and 14 may be controlled.

When fluid under pressure is admitted into space 9 by opening valve 15 on pipe 10 and valve 20 16 is adjusted to permit the fluid of flow out from space 14 under the piston, the pressure 25 in space 9 will cause the reciprocating core E to rise, and when, by reverse adjustment of valves 15 and 16, fluid under pressure is admitted into space 14 through pipe 13 and permitted to escape 30 from space 9 through pipe 10, the reciprocating core E will fall. The reciprocating core E is provided with an extension E' slightly smaller in diameter and normally positioned within the flask A, and this difference in diameter serves a purpose to be explained later.

The cone shaped closure 17 is secured to the top of core E and extension core E' is secured to the cone 17 by a spider 18 carried by the cone 35 a short distance above the upper end of core E, thus leaving an annular space through which concrete may flow from the interior of the core extension E' into the space between this extension and the walls of flask A. A heavy piston 40 ton 19 having a cup leather 20 or other packing is provided to bear upon a batch of concrete mix H dumped into the interior of the core extension E' and form an air tight seal when a vacuum is produced below the cup leather, and 45 the reciprocating core extension E' passes up through a stuffing box 21 formed on the bolted cover 22 which closes the upper end of the mold space between the core and the inner walls of the flask A in which space the concrete forming 50 the pipe is compressed with great force, all as will be explained later. A pipe 23 leads to a vacuum tank, not shown, and a ring of porous material 24, which is permeable to air and steam but acts as a dam for the concrete, is placed in 55 the top of the mold space.

Steam may be admitted to the space 25 between the core E and cylinder F by way of pipe 26 and flexible hose 27, for a purpose hereinafter appearing.

It is well known that concrete, as usually cast, is quite porous. This porosity may be reduced by tamping or by vibration, which causes the air bubbles, liquid and lighter cement particles to rise to the top of the mass in the form of laitance, which should be removed to get a strong, uniform, concrete product.

It is also of importance in obtaining such a product have the casting of the same continuous from start to finish, for, if any stoppage of the flow of the plastic concrete into the mold occurs, a film of laitance will rise to the top of the layer, thus forming a thin stratum of weak concrete which might act as a parting place.

In the production of castings according to the invention as will now be described, a much sounder air and gas tight pipe can be manufactured of concrete than has heretofore been obtained, and with or without metal reinforcing in the walls thereof, as desired.

The various parts of the apparatus having been assembled over the well or pit, as shown, with metal reinforcement in place in the mold space, if desired, a batch H of properly mixed concrete, sufficient to make the walls of the pipe, is dumped into the interior of the core extension E' and the piston 19 set in place on top of the batch. The valve on pipe 23 is now opened to the vacuum tank, which draws a partial vacuum in the space between the core E' and flask A and throughout the batch of concrete in the core. At the same time a pressure fluid, preferably water, is admitted into the space 9 and the reciprocating core begins its upward travel. Atmospheric pressure, due to the vacuum now formed beneath piston 19, forces the concrete downward, and through the medium of the cone 17 it passes annularly outwardly into the mold space between the core E-E' and the walls of the flask A. An electric vibrator, not shown, attached to the flask A at an appropriate point, vibrates the plastic mass in the mold space and permits any air bubbles or gases that might have been trapped in the batch of concrete to rise and be delivered through pipe 23 into the vacuum tank.

The rising speed of the reciprocating core is so regulated as to permit the concrete to flow into the mold space at any desired rate, and it should be slow enough to permit the air or gas bubbles to be drawn off so as to form a dense wall. This density will be still further increased as the lower part E of the core rises, due to the fact that it is slightly larger in diameter than the extension E' of the core and acts to compress the already cast section of the pipe wall radially outwardly.

As the core starts on its upward stroke steam may be admitted into the space 25 through conduit 26-27. The heat of the steam transmitted through the wall of the core E to the concrete in the mold space causes the water in the concrete as it is molded to evaporate and the moisture thus freed is exhausted through pipe 23 to the vacuum tank as rapidly as formed.

When the core reaches the top of its stroke the heat of the steam causes the core E to expand, still further compressing and increasing the density of the molded concrete. The steam heating should be continued until all evaporation ceases.

To make an absolutely liquid and gas tight pipe

it is necessary to fill all the pores near the inner surface of the pipe wall with a sealing compound, which may be composed of any suitable plastic to suit the special purpose for which the pipe is to be used.

It has been found that an asphaltum compound is very satisfactory where the pipe is to be used as a water main. In accordance with the invention, this compound may be employed in the following manner: The asphaltum is mixed with a small amount of dead oil and a quantity of powdered pumice or slaked lime, to make a compound which will melt at about 175° F. The core E-E' and the inner surface of the mold A, are painted with a layer of this compound which quickly hardens into an enamel-like coating and holds its place on the core and mold until the pipe is cast. When the core is raised to its top position, with the steam turned on, a rapid dehydration of the concrete occurs, but as long as there is some moisture in the concrete mass the asphaltic compound will not melt. However, as soon as the concrete is dry, the steam will rapidly raise the temperature sufficiently to melt the compound and it will be absorbed into the inner 20 and outer surfaces of the casting and leave annular spaces between the casting and the walls of the core E and flask A. Additional compound may now be forced into these spaces at high temperature until they are completely filled under any pressure which may be desired. The steam is now turned off, and as soon as the compound has cooled slightly and the core E has assumed its normal size, due to cooling, the core is withdrawn, leaving an enamel surface. If the pipe is to be used as a conduit for the installation of electric wires, this surface forms an effective insulation, and it also prevents electrolysis or rust from affecting the metal reinforcement, if such is embodied in the pipe as cast. If the pipe is to be used for conveying gas, volatile oils, or acidulous liquids, different kinds of known and available plastics may be used to fill the pores and enamel the inner surface of the pipe.

The casting apparatus illustrated in Figs. 3 and 4 embodies modifications adapted to the casting of the more common type of bell and spigot drain pipe, and also a modified means for more rapidly forcing the concrete into the mold space between the continuous core E' and flask A'. In this modified form the core is provided with a rotary distributor 28 carrying a series of involute shaped vanes or blades 29. This distributor is preferably made of wear-resistant chilled steel or iron, as the involute shaped blades act as cams to push the abrasive concrete radially outwardly through openings 30 formed circumferentially of the core E'.

The distributor 28 is carried by a head 31 which is provided with ring gear teeth 32 on the inner surface of its depending flange 33, and with these teeth a pinion 34 meshes, as shown. The pinion 34 is fixed on one end of a short shaft 35 having a bearing in the fixed septum 36, and the other end of this shaft 35 is welded to a tube 37 having a sliding fit upon a squared or splined shaft 38 which extends through a stuffing box 39 in the bottom 40 of the core E' and is driven by the bevel gears 41-42 through the drive shaft 43 which may be driven by any appropriate type of transmission.

The head 31 revolves freely on a bearing 31 secured to the head of the hydraulic cylinder F' which reciprocates upon the piston G', in the same manner as already described in relation to Fig. 1, to raise and lower the core E'.

This modified apparatus is operated as follows: With the core E² in its lowered position, as shown, a batch of ready mixed concrete, sufficient in quantity to make the pipe, is dumped into the interior of the core on top of the distributor 28. The vacuum operated piston 19' is now set in position upon the batch and a partial vacuum created through pipe 23' within the mold space. This starts a pull on the plastic concrete of the batch to draw it into the mold space and at the same time starts to pull on the piston 19' to exert pressure on top of the batch of concrete, thus forcing the concrete radially through the series of ports 30. Vibrators now being applied to the walls of the flask, the concrete settles in the mold space and the core is started to move upward as previously described in relation to Fig. 1. The downward pressure on piston 19' combined with the upward movement of the core is sufficient to fill the mold space provided the concrete is fairly wet and free flowing, but if the concrete mixture is what is termed a "dry mix," with little water content, it may require greater power to force the concrete through the ports 30 and around the metal reinforcing means, if such are used. This is accomplished by rotation of the distributor 28, the involute vanes 29 of which will force the concrete through the ports and pack it tightly in the mold space.

If steam is now admitted through pipe 27' into the steam space 25' in the core, the moisture in the cast concrete will quickly be evaporated and drawn off into the vacuum tank, so that, as previously described, an inner lining of a more impervious compound may be forced in to thoroughly fill all pores of the concrete pipe nearest the heated core walls. This operation is provided for in the modified form of apparatus by means of a pipe 44 through which grout or other desired compound may be forced up into the annular perforated pipe 45 and from there outwardly through numerous small mating orifices 46 in the core wall.

Various changes and modifications are considered to be within the principle of the invention and the scope of the following claims.

What I claim is:

1. Apparatus for molding tubular concrete bodies, including a flask, a tubular core of a length substantially twice that of the flask and reciprocative axially of said flask and serving therewith to provide a tubular mold space, the interior of substantially one-half the length of said tubular core serving as a receptacle for receiving a batch of concrete mix adequate to form

the said tubular body, and means for reciprocating said core, said core being provided substantially midway of its length with means for ejecting the concrete of said batch radially outwardly to fill the mold space progressively from the bottom upwardly as the core moves upon its upward reciprocation, the length of said core providing for its contact with the concrete in the mold space throughout the entire molding operation.

5 2. Apparatus as claimed in claim 1, in which there are provided means for subjecting the mold space to suction and means for subjecting said batch of concrete mix to atmospheric pressure.

15 3. Apparatus as claimed in claim 1, in which said core is provided with a piston furnishing a substantially hermetic seal above the batch of concrete mix, and the mold space is connected with suction-producing means.

20 4. Apparatus as claimed in claim 1, in which a portion of the core below said radially ejecting means is of greater diameter than the portion above said means, whereby as the core moves upon its upward molding reciprocation its portion of greater diameter will radially compress the concrete progressively deposited in the mold space.

25 5. Apparatus as claimed in claim 1, in which the portion of the core below said radially ejecting means is connected with a source of heating fluid, whereby, as the mold is progressively filled the concrete therein may be dehydrated by the application of heat through said core.

30 6. Apparatus as claimed in claim 1, in which 35 a rotary distributor having a plurality of off-standing impeller vanes is provided as a part of said radially ejecting means.

40 7. Apparatus for molding tubular concrete bodies, including a flask, and a tubular core of a length substantially twice that of the flask and arranged axially of said flask and serving therewith to provide a tubular mold, the interior of said core throughout substantially one-half of its length serving as a receptacle for receiving 45 a batch of concrete mix adequate to form the said tubular body, and means for causing relative axial reciprocation between said flask and core, said core being provided substantially midway of its length with means thus located adjacent to one end of the mold space at one limit of such reciprocation for ejecting the concrete of said batch radially outwardly to fill the mold space progressively from said end longitudinally as such reciprocation progresses.

55 55 SIMON LAKE.
